Attorney.

UNITED STATES PATENT OFFICE.

THEODORE KOCHENKOFF, OF NEW YORK, N. Y.

CUFF-BUTTON.

1,323,699.

Specification of Letters Patent.

Patented Dec. 2, 1919.

Application filed May 13, 1919. Serial No. 296,730.

To all whom it may concern:

Be it known that I, THEODORE KOCHENKOFF, citizen of the United States, residing at New York, New York county, New York 5 State, have invented certain new and useful Improvements in Cuff-Buttons, of which the following is a specification.

This invention relates to cuff buttons and links and its object is to provide means by 10 which the device may collapse and decrease in length when necessary to reduce the distance between the button holes or it may be lengthened to provide a greater distance between the buttons above the elbow when the 15 sleeves are raised and without loosening the connection. This is made possible by constructing the links of telescopic tubes of the desired number of sections and securing them against separation but adapting them 20 to close in on themselves, as will be more fully described in the following specification, set forth in the claims and illustrated in the accompanying drawings which form a part of this application and wherein:

25 Figure 1 is a side view of the improved cuff buttons expanded.

Fig. 2 is a similar view in section.

Fig. 3 is a view of the links compressed and collapsed.

30 Fig. 4 is a plan view of the links separated.

Fig. 5 is a view of a blank of a link.

Fig. 6 is a side view of a modified form.

35 Fig. 7 is a similar view of another modified form partly in section.

While linen or other cuffs will generally remain in a closed position and where a short link is sufficient for a cuff button, there are occasions where the same will require 40 expansion, particularly when the hand is passed through the cuff or it is desired to draw up the sleeves to elevate the cuffs from the wrists.

The device shown in the drawings permits 45 of this expansion and shows the two buttons 10 and 10' at each end of the intermediate links and these buttons may be of appropriate size and design. The button 10' is shown as being pivoted to the link 11 by 50 means of a pin 12' so it may be thrown into a longitudinal position to enter the button holes to appropriately locate the cuff buttons in the cuff.

The links consist of tubes 11, 12, 13 and 14 55 of different sizes so that they telescope and

assume the approximate size and shape shown in Fig. 3, and they are preferably arc-shaped to conform with the contour of the wrist or arm of the owner. As best shown in Fig. 4 the tubes 11, 12 and 13 are slotted 60 and the tubes 14, 13 and 12 are provided at their contiguous ends with lips 15 to be bent downward to enter the slots of the smaller tube and it will be seen that in the use of the four links there are three slots 16 and three 65 lips. The links are free to move inward or outward and are limited by the length of the slot only, the smaller links telescoping within the larger but the size of the tube may be such that the movement is slow in consequence of friction or tightness of fit and it will require manual effort to close or open the buttons. 70

The construction of the intermediate links is illustrated in Fig. 5 where the blank of 75 the tube is shown with studs 17 and 18, the former for the lip 15 and front end of the slot and the latter for the rear terminus of the slot. This blank is rolled into cylindrical shape for the tube. The blank for 80 link 11 has no lip but two studs, and the link 14 has no studs because there is no slot to be formed.

The number of links for the button may be varied and also the shape, as shown in 85 Fig. 6 where three links are used and adapted to operate in a straight line, and they are provided with appropriate lips and slots as above described.

The modified form shown in Fig. 7 provides tubes with an enlarged outer end and a reduced inner end so that the links 20 and 21 will freely pass into the tubes 21 and 22 respectively but will be arrested on account of the enlarged heads 23 being arrested by 95 the contracted inner ends 24.

It is evident that other means may be adopted to hold the tubular links together without departing from the essential features above described or from the scope of 100 the appended claims.

What I claim as new is:

1. In cuff buttons, the combination of a series of tubular sections telescoping within themselves, buttons at the extremities of the 105 series, and a lip at the end of the sections and adapted to engage the adjacent section and prevent their separation.

2. In cuff buttons, the combination of tubular telescopic sections having buttons at 110

each extremity, and engaging means at the end of each section adapted to enter a slot in the adjacent section.

3. In cuff buttons, the combination of 5 tubular telescopic sections with a button at the end of the first and last sections, and a lip at the end of each larger section and adapted to play in a slot in the telescopic smaller section and prevent its separation.

10 4. In cuff buttons, the combination with a set of buttons, of tubular links of different diameters adapted to telescope within each other and having slots, and means playing in the slots preventing the separation of the 15 links.

5. In cuff buttons, the combination of a pair of buttons, a tube connected with one of the buttons and having a lip, and smaller tubes adapted to telescope within the first tube and having slots and lips to limit their movement and carrying the other button. 20

In testimony whereof, I have signed my name to this specification in the presence of two subscribing witnesses, this 9th day of May, 1919.

THEODORE KOCHENKOFF.
